UNITED STATES PATENT OFFICE.

JOSEPH J. CAUDLE, OF RICHMOND, VIRGINIA.

DIRECTION SIGNAL.

Application filed June 26, 1925. Serial No. 39,756.

This invention relates to signaling devices for vehicles and particularly to a signal adapted to be mounted at the side of an automobile for indicating the driver's intended course to traffic in rear front and left side of him.

One object of the invention is to produce a signaling device having a movable arm or semaphore which may be caused to assume 10 any one of a plurality of positions each of which will impart a desired signal or information to traffic at the rear, front and left side of the car on which the device is carried. In conjunction with such arm 15 there is also provided a lamp which will display any one of a number of colored lights, the color displayed depending upon the position assumed by said arm so that the different colors, at night, may be utilized 20 for giving the signal given by the arm during the day.

With this and other objects in view the present invention consists in certain novel details of construction and combinations and 25 arrangements of parts, all of which will be hereinafter more fully described and the novel features thereof particularly pointed out in the appended claims.

In the accompanying drawings,—

30 Fig. 1 is a front view of the device, only a portion of the machine frame being shown. The semaphore or signaling arm is shown in full in its lowermost position and in dotted lines in the other positions it may assume.

Fig. 2 is a side view of the exterior of the vehicle.

Fig. 3 is a sectional view on the line 3—3 of Fig. 2.

40 Fig. 4 is a sectional view on the line 4—4 of Fig. 1.

Fig. 5 is a sectional view on the line 5—5 of Fig. 1, the arm in this figure, however, being shown in its horizontal position.

45 Fig. 6 is a sectional view on the line 6—6 of Fig. 5.

Fig. 7 is a sectional view on the line 7—7 of Fig. 5.

Fig. 8 is a detail view with the arm moved 50 a short distance in its horizontal position.

Fig. 9 is a transverse section of the lamp.

Fig. 10 is a longitudinal sectional view 55 of the lamp.

Fig. 11 is a plan view of a modified form of the device particularly adapted for use on open cars.

Fig. 12 is an elevational view of the modified construction.

As has before been generally described the device comprises an arm or semaphore 30 which is adapted to be moved to any one of a plurality of positions in a plane at an angle to the horizontal, the arm usually being adapted to be positioned in a horizontal plane to indicate that the driver intends to stop; to a position where it extends upwardly at an angle of approximately 45° to the horizontal to indicate that the driver is about to make a left hand turn; and to a position where it extends down at an angle 70 of approximately 45° to the horizontal to indicate that the driver is about to make a right hand turn and to a substantially depending vertical position when it is not intended to give a signal. In the preferred 75 construction said arm or semaphore 10 is pivoted on a horizontal axis, as on the end of a shaft 11 which is journaled in a supporting frame 12 located at the exterior 80 of the frame or partition 13 of the vertical body, this supporting frame being attached to the vehicle body as will be later described. While various mechanisms may be employed for swinging arm 10 about its pivotal center, that shown in the present 85 instance comprises a gear 14 fast on shaft 11 and adapted to be rotated by a gear such as worm 15 which is mounted on a shaft 16 journaled in the supporting frame 12 at right angles to shaft 11. This shaft 16 90 extends through the partition 13 of the car body, its rear end being located adjacent the driver's seat and on this inner end of the shaft is a crank 17 easily accessible to the driver so that he may rotate the same 95 and impart the desired movement to the semaphore or arm 10. To hold the arm 10 in any of its desired positions there is a notched segmental member 18 on the inner end of the shaft 16 and the crank 17 has 100 a movable lug 19 which is yieldingly maintained in engagement with the notched surface of said segmental member whereby when the arm is moved to any one of its positions the lug 19 will engage in one of 105 the notches of the segment and prevent movement of the arm until it is withdrawn therefrom.

During the day, the arm is plainly visible to traffic in rear, front and left side of the 110 vehicle on which the device is mounted so that the signal intended to be imparted by

the position to which the arm is moved is readily made known. However, this is not true at night and for this reason a lamp 20 is provided at the outer end of the arm. 5 The shade or globe 21 of said lamp has a multiplicity of vari-colored lenses, one color for each of the signaling positions of the arm and said shade is adapted to be revolved about the lamp in order to display the particular color which has the same significance as the position which is occupied by the arm at the time such color is exhibited. This rotation or revolving of the lamp shade is effected automatically upon actuation of the 10 operating crank 17 so that the turning of the crank by the driver is the only operation he need perform to move the arm to its desired position and to display the desired colored light.

20 The preferred arrangement for accomplishing the simultaneous movement of the arm and shade consists of a sleeve 22 rotatably secured on the arm 10, the outer end of said sleeve 22 supporting the shade or globe 21 and the inner end of said sleeve being formed with a collar 23 and a pair of teeth 24—34. The collar 23 has two flattened faces 25—35 with a lug 26 formed between them and these elements are adapted 25 to cooperate with a recessed arcuate surface 27 of a segmental shaped member 28 mounted on the supporting frame 12. Also supported on the frame is a pin 29, this pin and the notch 30 in the arcuate surface 27 being 30 located at the point occupied by the frame 10 when the latter is in its horizontal position.

Assuming the arm 10 to be in its depending vertical position (the position occupied by it when no signal is to be given) it will 35 be seen that the flat face 25 of the collar on the sleeve 22 abuts against the arcuate surface 27 and prevents rotation of said sleeve but if the crank 17, which is in the lowermost notch in member 18, is now moved to the next higher notch the arm 10 will be moved approximately 45° to the position to indicate that a right hand turn is to be made. This 40 movement of the arm, however, will not result in any turning of the sleeve or lamp shade, the flat face 25 of the collar remaining against the arcuate surface 27 but if the crank should be moved to the next higher notch to bring the arm to the horizontal position it will be seen that lower tooth 24 45 will engage the pin 29 just before arm 10 reaches the horizontal with the result that the sleeve 22 will be rotated on the arm one-sixth of a complete revolution. This partial rotation of the sleeve causes the lug 26 on the sleeve to enter the notch 30 in the arcuate surface 27 and if the crank 17 should again be moved to the uppermost notch in segmental member 18 to position the arm in its uppermost position, the lug 26 engaging the shoulder formed by the upper side of the 50

notch 30 will tend to restrain movement of sleeve 22 with arm 10 with the result that said sleeve will be given a further rotation of approximately one-sixth of a complete revolution and the upper flat face 35 of the 70 collar 23 will be brought into engagement with the upper portion of the surface of the arcuate member 27 to prevent accidental rotation of the lamp shade so long as the arm is in this uppermost position. 75

When crank 17 is moved downward to return the arm 10 to its depending vertical position the other tooth 34 on the sleeve engages the pin 29 as the arm approaches the horizontal and effects a one-sixth revolution 80 of the sleeve and shade in a vertical direction, bringing the lug 26 again into the notch 30 so that as the arm moves below the notch the lug engaging the lower side of said notch will effect a further one-sixth revolution of 85 the arm and sleeve to restore the lamp shade to the position originally occupied by it.

From the foregoing it will be seen that the lamp shade is given a one-sixth revolution each time it is moved from one position to 90 its next adjacent position. Therefore, the shade is divided into six segments, three sets of diametrically opposed lenses being arranged around the shades with the lenses of each pair of the same color so that the 95 same color light will be displayed fore and aft of the vehicle. To prevent other confusing lights being shown or displayed by the lamp a shield or screen 31 is secured in the interior of the lamp in fixed relation 100 to the source of light and the shade. This shade or screen is formed with openings 32 which will permit rays of light to be projected fore and aft of the vehicle but which will prevent the projection of light to the 105 side. This screen can be fixedly secured to the outer extremity of the arm 10 as by a set screw 33 and, as will be apparent, when the arm 10 is moved to one of its positions one of the sets of lenses will be brought into 110 registry with the openings 32 to display the desired colored light.

Any desired colors may, of course, be used for the lenses of the lamp shade, although if the horizontal position of the arm is to 115 indicate "stop", it is preferred a red lens be arranged in the shade so as to be brought into registry with openings 32 when the arm is in horizontal position as this color is most generally used at the present day 120 in various stop signals now used on automobiles.

In the modified form of construction for use on cars of the open type the segmental member 28 having the arcuate surface 27 is 125 supported by a clamp 40 which may be clipped to one of the upright members of the windshield frame, this arcuate surface being arranged concentrically of the pivotal center of a shaft or swivel pin 41 journaled 130

in the supporting frame 12, the swivel pin carrying the arm 10 in the same manner as the arm is supported by shaft 11 in the preferred construction. The sleeve 22 carrying the lamp shade is journaled on arm 10 and is provided with the teeth 24-34 and the collar 23 which cooperate with the pin 29, the arcuate surface 27, and the notch 30 in said surface, in the same manner as in the preferred construction to effect the rotation of said sleeve and lamp shade. In this modified form, however, the gears, the shaft 16 and the other parts that are located on the interior of the car in the closed car type of the device are omitted and in lieu thereof the inner end of arm 10 has pivotally secured thereon a handle 42 which is yieldingly held by a spring 43 in engagement with a continuation of the arcuate surface 27 in which there are a series of notches 44 in which the proximate end 45 of handle 42 may engage to hold arm 10 in any of its adjusted positions.

From the foregoing it is readily apparent that the present signaling device is susceptible of use either during the day or at night with the advantage that it is located in identically the same way at all times to give the same signal. In other words, if the lights are to be used for signals as at night time instead of the positions of the arm being used as in the day time the driver does not have to carry in his mind a different series of operations. He always operates the device in the same way at all times. Furthermore, the present arrangement for effecting the rotation of the lamp shade to display the various colors is positive in its action; functions simply by the driver operating the crank 17; and, insures the proper colored light being displayed without any adjustments on the part of the operator except in so far as he is called upon to move the crank into registry with one of the notches in the segmental member for locking the operating handle in its various positions.

What I claim is:

1. In a signaling device for vehicles, the combination of an arm at the side of the vehicle movable in a plane at an angle to the horizontal, a light carried at the outer extremity of said arm, a sleeve rotatable on said arm, a multi-colored shade on said sleeve enclosing said light, means for simultaneously raising or lowering said arm and revolving said sleeve on said arm and means for locking said sleeve and shade against rotation at any one of a series of points in their rotation about their centers.

2. In a signaling device for vehicles, the combination of an arm at the side of the vehicle movable in a plane at an angle to the horizontal, a light carried at the outer extremity of said arm, a sleeve rotatable on said arm, a multi-colored shade on said

sleeve enclosing said light, means for simultaneously raising or lowering said arm and revolving said sleeve on said arm, means for locking said sleeve and shade against rotation at any one of a desired number of 70 points in their rotation about their centers and screens carried by said arm in proximity to said light to prevent passage of rays through certain portions of the multi-colored shade. 75

3. In a signaling device for vehicles, the combination of a supporting frame, an arm pivoted on the frame to move in a vertical plane, a sleeve on said arm, a light carried on the arm, a shade on said sleeve enclosing 80 said light, connections operable from the interior of the vehicle for raising or lowering said arm, a pin on said supporting frame, and a pair of cooperating teeth on said sleeve engageable with said pin to revolve said sleeve and shade on the arm as the latter is raised or lowered.

4. In a signaling device for vehicles, the combination of a supporting frame, an arm pivoted on said frame, means for moving 90 said arm to any one of a plurality of positions in a plane at an angle to the horizontal, a source of light carried by said arm and having a shade comprising vari-colored lenses the colors corresponding in numbers 95 to the number of positions said arm may assume, a screen partly surrounding said light, means for revolving said shade to position a certain color in registry with the open portions of the screen depending upon 100 the position of said arm and means for locking said sleeve and shade against rotation at any one of a series of points in their rotation about their centers.

5. In a signaling device for vehicles, the combination of a supporting frame, an arm pivoted on said frame, means for moving said arm to any one of a plurality of positions in a plane at an angle to the horizontal, a source of light carried by said arm and having a shade comprising vari-colored lenses, the colors corresponding in numbers 105 to the number of positions said arm may assume, a screen partly surrounding said light, means for revolving said shade to display a different color for each position the arm may assume and means for locking said sleeve and shade against rotation at any one of a series of points in their rotation about their centers. 110

6. In a signaling device for vehicles, the combination of an arm positioned at the side of the car and movable in a plane at an angle to the horizontal whereby said arm may assume any one of a plurality of signaling positions, means for swinging said arm to move it to any one of said positions, a lamp carried on said arm and having a shade composed of varied colors, one color 115 for each position the arm may assume, a 120

screen partially surrounding the source of light in said lamp, means operable by the movement of said arm to revolve said shade to display a different color for each position of the arm and means for locking said sleeve and shade against rotation at any one of a series of points in their rotation about their centers.

7. In a signaling device for vehicles, the combination of an arm positioned at the side of the car and movable in a plane at an angle to the horizontal whereby said arm may assume any one of a plurality of signaling positions, means for swinging said arm to move it to any one of said positions, a lamp carried on said arm, a sleeve on said arm, a shade on said sleeve for said lamp, said shade having a plurality of colored lenses, a screen partially surrounding the source of light for said lamp, means operable by movement of said arm to revolve the sleeve and shade to display a different color for each position the arm may assume and means for locking said sleeve and shade against rotation at any one of a series of points in their rotation about their centers.

8. In a signaling device for vehicles, the combination of an arm positioned at the side of the car and movable in a plane at an angle to the horizontal whereby said arm may assume any one of a plurality of signaling positions, means for swinging said arm to move it to any one of said positions, a lamp carried on said arm and having a shade composed of varied colors, one color for each position the arm may assume, said shade being rotatable about the source of light of the lamp, means operable by the movement of said arm to revolve said shade to display a different color for each position of the arm and means for locking said sleeve and shade against rotation at any one of a series of points in their rotation about their centers.

9. In a signaling device for vehicles, a supporting frame adapted to be attached to the vehicle, a swinging arm pivoted on said frame, a sleeve rotatable on said arm, a lamp on the arm, a lamp shade on said sleeve, means for revolving said sleeve and shade as the arm is moved about its pivotal center to any one of a plurality of positions, and means on said sleeve and frame for locking said sleeve and shade against rotation while the arm is in any one of its positions.

10. In a signaling device for vehicles, a supporting frame adapted to be attached to the vehicle, a swinging arm pivoted on said frame, a sleeve rotatable on said arm, a lamp on the arm, a lamp shade on said sleeve, means for revolving said sleeve and shade as the arm is moved about its pivotal center to any one of a plurality of positions, and means for locking said sleeve and shade

against rotation while the arm is in any one of its positions, said locking means comprising a flat surface arranged concentric to the pivotal center of the arm, said surface having a recess therein, a collar on said sleeve having a lug formed thereon adapted to extend into said recess when the arm is in one position and said collar having a flattened surface adapted to abut said arcuate flat surface at the side of said recess when said lug is moved out of the recess.

11. In a signaling device for vehicles, a supporting frame adapted to be attached to the vehicle, a swinging arm pivoted on said frame, a sleeve rotatable on said arm, a lamp on the arm, a lamp shade on said sleeve, means for revolving said sleeve and shade as the arm is moved about its pivotal center to any one of a plurality of positions, and means for locking said sleeve and shade against rotation while the arm is in any one of its positions, said locking means comprising an arcuate flat surface arranged concentric to the pivotal center of the arm, said surface having a recess therein, a collar on said sleeve having a lug thereon adapted to enter said recess when said arm is in an intermediate position and said collar having a flattened face at each side of said lug to engage said arcuate flat surface at the sides of said recess when said arm is above or below its intermediate position.

12. In a signaling device for vehicles, a supporting frame, a swinging arm pivoted on the frame, a sleeve rotatable on the arm, a lamp on the arm having a shade carried by said sleeve, means revolving said sleeve and shade as the arm is moved about its pivotal center to any one of a plurality of positions, and means for locking the shade against rotation while the arm is in any of its positions, said means for revolving the sleeve comprising a pin on the frame, and a pair of teeth on the sleeve engageable with said pin to impart a partial rotation to the sleeve when the arm is moved about its center.

13. In a signaling device for vehicles, a supporting frame adapted to be attached to the vehicle, a swinging arm pivoted on the frame, a sleeve rotatable on said arm, a lamp on the arm, said lamp having a shade supported by and rotatable with said sleeve, means for revolving said sleeve and shade as the arm is moved about its pivotal center to any one of a plurality of positions, and means for locking said sleeve and shade against rotation while the arm is located in any one of its positions, said means for revolving the sleeve and shade comprising a pin on said frame, a pair of teeth carried by the sleeve and engaged with the opposite sides of said pin to impart a partial rotation to the sleeve when the arm is moved from one position to another, a pair

of stops carried by said frame and a lug projecting from said sleeve and adapted to enter between said stops whereby one of said stops will hold said sleeve and again partially rotate it upon further movement of the arm about its center of swinging movement.

14. In a signaling device for vehicles, a supporting frame adapted to be mounted on the vehicle, a lamp movable about a pivotal center to a plurality of positions in a plane at an angle to the horizontal, the shade of said lamp having a plurality of vari-colored lenses corresponding in number to the number of positions said lamp may assume, means for revolving the shade of said lamp to display a different colored light in each one of the positions assumed by said lamp and means for locking said sleeve and shade against rotation at any one of a series of points in their rotation about their centers.

15. In a signaling device for vehicles, the combination of a supporting frame adapted to be mounted at the exterior of the side of a car of the closed type, a shaft journaled in said frame, an arm mounted on said shaft, a second shaft journaled in said frame and extending into the interior of the car, an operating lever at the inner end of the inwardly extending shaft, means for transmitting motion from said shaft to the shaft carrying said arm whereby said arm may be moved to any one of a plurality of positions in a plane at an angle to the horizontal, a source of light carried by said arm, a shade surrounding said source of light, means for pivotally revolving said shade around said source of light as said arm is moved from one position to another and means for locking the sleeve and shade in their several positions.

16. In a signaling device for vehicles, the combination of a supporting frame adapted to be mounted at the exterior of the side of a car of the closed type, a shaft journaled in said frame, an arm mounted on said shaft, a second shaft journaled in said frame and extending into the interior of the car, an operating lever at the inner end of the inwardly extending shaft, means for trans-

mitting motion from said shaft to the shaft carrying said arm whereby said arm may be moved to any one of a plurality of positions in a plane at an angle to the horizontal, a source of light carried by said arm, a sleeve rotatable on said arm, a shade mounted on the sleeve and surrounding said source of light, an abutment on the supporting frame, teeth on said sleeve adapted to engage said abutment and partially rotate said sleeve in opposite directions as said arm passes said pin, a pair of spaced abutments on said supporting frame, and a projection on said sleeve adapted to engage said abutments to further rotate said sleeve on the arm as the latter passes said abutments.

17. In a signaling device for vehicles, the combination of a supporting frame adapted to be mounted at the exterior of the side of a car of the closed type, a shaft journaled in said frame, an arm mounted on said shaft, a second shaft journaled in said frame and extending into the interior of the car, an operating lever at the inner end of the inwardly extending shaft, means for transmitting motion from said shaft to the shaft carrying said arm whereby said arm may be moved to any one of a plurality of positions in a plane at an angle to the horizontal, a source of light carried by said arm, a sleeve rotatable on said arm, a shade mounted on said sleeve and surrounding said source of light, an arcuate flat surface arranged concentrically of the pivotal center of said arm, there being a recess in said arcuate flat surface forming opposed abutments, a pin carried by said supporting frame, teeth on said sleeve engageable with said pin to partially rotate said sleeve as the arm passes said pin, a projection on said sleeve engageable with the abutments formed by the recess in said arcuate surface for further rotating said sleeve as the arm passes said abutments, and a collar formed on said sleeve having substantially flat faces adapted to engage the arcuate flat surface at opposite sides of said notch to prevent rotation of said sleeve after the arm has passed to either side of said pin and notch.

JOSEPH J. CAUDLE.
